[57] CLAIM

The ornamental design for a combined vibrator and massager, as shown and described.

DESCRIPTION

FIG. 1 is a top plan view of a combined vibrator and massager, showing our new design, with the double diagonal lines representing shadowing;

FIG. 2 is a side view thereof, the opposite side view being a mirror image;

FIG. 3 is a bottom view thereof;

FIG. 4 is a front end view thereof;

FIG. 5 is a back end view thereof;

FIG. 6 is a top plan view of a second embodiment of FIG. 1, with the singular diagonal lines representing brown or tan coloring;

FIG. 7 is a side view thereof, the opposite side view being a mirror image;

FIG. 8 is a bottom view thereof;

FIG. 9 is a front end view thereof; and,

FIG. 10 is a back end view thereof.
